(57) **CLAIM**

The ornamental design for a cartridge sleeve as shown and
described.

DESCRIPTION

FIG. 1 is a top perspective view of a cartridge sleeve in
accordance with our new design;

FIG. 2 is an enlarged top view thereof;

FIG. 3 is an enlarged bottom view thereof;

FIG. 4 is a front view thereof, the back view thereof is
identical to the front view; and,

FIG. 5 is a right side view thereof, the left side view thereof
is identical to the right side view.

The broken lines in the drawings illustrate portions of the
cartridge sleeve that form no part of the claimed design.

1 Claim, 5 Drawing Sheets
